UNITED STATES PATENT OFFICE.

SPENCER OTIS, OF CHICAGO, ILLINOIS, ASSIGNOR TO NATIONAL DUMP CAR COMPANY, OF CHICAGO, ILLINOIS, A CORPORATION OF MAINE.

DUMP-CAR.

No. 908,489.

Specification of Letters Patent.

Patented Jan. 5, 1909.

Application filed September 6, 1907. Serial No. 291,623.

To all whom it may concern:

Be it known that I, SPENCER OTIS, a citizen of the United States, residing at Chicago, in the county of Cook and State of Illinois, 5 have invented certain new and useful Improvements in Dump-Cars, of which the following is a specification.

My invention relates to railway cars, and more particularly to tilting dump cars, the 10 object being to provide an improved car of this type.

Another object of my invention is to provide a box car that can be used in an ordinary way when desired or can be used as a 15 dump car when desired.

Another object of my invention is to provide a side bearing that shall be securely held in position under normal circumstances, but that may be displaced to facilitate dumping.

20 These and other objects of my invention will be made apparent in the following specification and claims.

Referring to the drawings—Figure 1 represents a cross section of my improved car; 25 and Fig. 2 is a detail showing the supporting connection between the truck frame and the car body.

The bolster 15 has a shallow spherical cup 16 in the middle of its upper surface in which 30 rests a corresponding convex spherical member 17 attached to the under side of a longitudinal center sill 18. Diagonal braces 18^a extend out from this center sill and support the cross sills 18^b. At each side of the bolster 15 stands a side bearing member 19 pivoted to the bolster at 20 and carrying a shoulder 21. The link 23 is pivoted to the bolster 35 at the point 22, and has connected to it another link 24, the outer end of which carries 40 a pin 25 which supports the shoulder 21 when the toggle joint formed by the two said links lies flat and extended on the bolster. A chain 26 has its ends attached to the ends 45 of the bolster 15 at the points 27 and passes over the pulleys 28 on the under side of the car body. On the same shaft with one of the pulleys 28 is a handle 29 with a ratchet and pawl connection 30 between it and the said pulley. On the cross sills 18^b the box car 31 50 is supported. It has side doors 32 pivoted along their upper edges, as shown, and swinging outwardly. The convex spherical bearing member 17 has laterally extending slots 17^a—shown in Fig. 2. The king-bolt

17^b projects up from the concave spherical bearing member 16 into this slot.

Under normal conditions the side bearing members 19 are upheld by the pins 25 under the respective shoulders 21, and it is obvious that the toggle joint which carries the said 60 pins will tend to lie flat on the bolster 15 and keep the pins in place. When it is desired to dump the car the toggles on one side are broken and the side bearing members 19 are thrown down, then by means of the handle 65 29 the pulley 28 is rotated in the proper direction and with a little start by this means the car tilts over and dumps through the swinging door on the opposite side. By means of the handle 29, the car may also be 70 righted after dumping. When the car goes around a curve the truck must of course rotate with reference to the car body around a vertical axis, and when the car dumps, there must be relative rotation around the longitudinal axis. The joint illustrated in Fig. 2 75 obviously permits both of these movements.

I claim:

1. A car comprising a truck, a car body pivotally mounted thereon so as to permit 80 lateral tilting, side bearing members fixed on the car body, and respectively opposed side bearing members on the truck, the latter being pivoted to the truck and having shoulders with co-acting stops to hold them in 85 place when desired.

2. A side bearing for a tilting dump car, comprising two opposed bearing members, one of them being pivotally mounted and having a shoulder, and a stop co-acting with 90 the shoulder.

3. A side bearing for a tilting dump car, comprising two opposed bearing members, one of them being pivotally mounted and having a shoulder, and a stop co-acting with 95 the shoulder, said stop being connected by a toggle joint to the same structure as the pivotally mounted bearing member.

4. In combination a car body, two trucks, a universal joint between each of said trucks 100 and said car body, side bearings mounted on said trucks, stops on said side bearings, members mounted on the trucks and coacting with said stops, means whereby said members can be disengaged from said stops, and means 105 for tilting the car body.

5. A car body, a center sill, transverse beams above and resting on said center sill,

said center sill constituting the sole supporting means of said car body, two trucks, universal joints between said trucks and center sill, side bearings mounted on said trucks, 5 means for moving said side bearings into and out of engagement with said car body, and means for tilting the car body.

6. A car having a pivotal support on a truck, so as to permit lateral tilting, a chain 10 with its ends attached at the sides of the truck and passing over a pulley on the car body, and controlling means attached to the pulley.

7. A car having a pivotal support on a truck so as to permit lateral tilting, a chain 15 with its ends attached at the sides of the truck and passing over a pulley on the car body, and a handle attached by a ratchet and pawl connection to the pulley.

20 8. A side bearing for a tilting dump car,

comprising a bearing member fixed on the car body, an opposed bearing member pivoted on the truck, a shoulder on the last-named member, a stop adapted to engage the shoulder, said stop being on the end of a 25 link which is pivoted to another link which in turn is pivoted to the truck frame so that the two links lie flat and extended on the truck frame when the stop engages the shoulder.

9. A car having a pivotal support on a truck so as to permit lateral tilting, a chain 30 with its ends attached at the sides of the truck and passing over a pulley on the car body, means attached to the pulley for rotating it, and means for holding it in any desired position.

SPENCER OTIS.
